UNITED STATES PATENT OFFICE.

GEORGE P. KINGSBURY, OF BROOKLYN, NEW YORK, ASSIGNOR TO MERGENTHALER LINOTYPE COMPANY, A CORPORATION OF NEW YORK.

TYPOGRAPHICAL MACHINE.

1,255,891.

Specification of Letters Patent. Patented Feb. 12, 1918.

Application filed December 4, 1916. Serial No. 134,823.

To all whom it may concern:

Be it known that I, GEORGE P. KINGSBURY, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States, No. 436,532, to O. Mergenthaler, wherein circulating matrices are released from a magazine in the order in which their characters are to appear in print and then assembled in line, the composed line transferred to the face of a mold, the mold filled with molten metal to 20 form a slug or linotype against the matrices which produce the type characters thereon, and the matrices thereafter elevated and returned through distributing mechanism to the magazine from which they 25 started.

More particularly, it relates to that class 30 of machines equipped with a plurality of magazines which are movably arranged so that any selected one thereof may be brought into operative relation to the assembling and distributing devices. Ordinarily, the magazines are disposed in the machine at an inclination of about forty-five degrees, and are movable in a straight path at right 35 angles to their plane of inclination; and to insure their movement in this manner, it has been the practice to make use of suitable guiding devices in addition to the shifting mechanism by which they are raised and 40 lowered.

My present invention is intended to avoid the use of such guiding devices and contemplates the provision of shifting mechanism of such character as will maintain or 45 guide the magazines in a perfectly straight path during their movements without the aid of any further or additional devices.

In the accompanying drawings, I have 50 shown my invention in preferred form and by way of example and as applied to a linotype machine, but obviously many changes and variations may be made therein and in its mode of application which will still be comprised within its spirit. Thus, the details thereof may be widely varied, and it

may be adapted to other forms of typographical machines, such as typesetters, typecasters and the like, which handle type or dies instead of matrices. Generally speaking, I desire it to be understood that 60 I do not limit myself to any specific form or embodiment, except in so far as such limitations are specified in the claims.

Referring to the drawings:

Figure 1 is a side elevation of a portion 65 of a linotype machine having my invention applied thereto;

Fig. 2 is a similar view showing the parts in different position;

Fig. 3 is a section on the line 3-3 of 70 Fig. 2; and

Fig. 4 is a top plan view of the parts with the magazines removed.

The matrices are stored according to font in the magazines A, B and C, which are 75 carried by the shift frame D. The lower magazine C rests directly upon the frame D, while the magazines A and B are mounted upon their customary base frames A¹ and B¹, which are pivotally connected at 80 their upper ends, as at A² and B², to upstanding projections D¹ of the shift frame and which rest at their lower ends upon the underlying magazines. The shift frame D is mounted in the supporting frame E and 85 is arranged to be moved toward and from the same to bring one or another of the magazines into operative relation to the assembler entrance G and the channel entrance F¹, which latter is pivoted to the 90 machine frame, as at F², and arranged in position to receive the matrices as they are released from the distributing mechanism F. The supporting frame E is sustained at its lower end upon a pair of adjusting 95 screws E³ and at its upper end upon a transverse rod E², being provided at opposite sides with set screws E⁴ bearing against the rod. The screws E³ and E⁴ may thus be used to locate the supporting frame in or 100 adjust it to its proper position in the machine frame.

As previously stated, my present invention relates chiefly to the mechanism for shifting the magazines, and it contemplates 105 the provision of such mechanism as will effect the raising and lowering of the magazines in a perfectly straight path without the aid or use of additional guiding devices. In the present instance, such mechanism is 110

mounted in the supporting frame E so as to retain all the advantages which exist in such construction, for example, the capability of adaptation to existing machines, without material change therein, the easy assemblage of the parts, etc.; but if preferred, it may be mounted directly in the machine frame. In carrying out my invention, I preferably employ two rotary peripheral cams H, arranged at opposite sides of the magazines and coöoperating with rollers D² journaled in arms projecting downwardly from the forward end of the magazine shift frame D (see particularly Fig. 3).

The cams H are fast upon a transverse rock shaft H¹ mounted to turn in bearings at the front end of the supporting frame E, and provided with an operating handle H⁴. The extent of the cams is such as to effect a change from the uppermost to the lowermost magazine, or vice versa, the rollers D² resting on the lowest points of the cams when the upper magazine is in operative position (Fig. 1), and on their highest points when the lowermost magazine is in such position (Fig. 2). When the middle magazine is in operative position, the rollers rest in depressions H² formed at corresponding points in the cams. The cams are thus constructed to register and hold the magazines in proper position when in use or operation, but if desired other mechanism of any of the well known forms may be employed for this purpose.

In addition to the cams H, I employ a system of toggles or jointed links H⁵, H⁶ and H⁷, each a replica of the other, to take part in the shifting of the magazines. These parts are duplicated at opposite sides of the magazines, and the description of one of them will therefore suffice. The jointed links or members H⁵ and H⁶ face in opposite directions and are both loosely mounted at their lower ends upon the cam shaft H¹, and connected at their upper ends to a common pivot stud H⁸ projecting from the magazine frame D at the front. The link or toggle H⁷ faces in the same direction as the link H⁵ and is pivoted respectively to the rear end of the magazine frame D, as at H⁹, and to the supporting frame E, as at H¹⁰. The links H⁵ and H⁷ are connected together by means of a longitudinal rod H¹¹ attached at its opposite ends to their respective joints. The third link or member H⁶ is provided at its joint and between its upper and lower sections with a roller H¹³ arranged in contact with a flange or track portion H¹² formed on the lower edge of the connecting link H¹¹.

The operation of the parts will now be clear: When the cams H are rotated to shift the magazines upwardly, the jointed link H⁵, due to its connection with the magazine shift frame D, is lengthened out, and the longitudinal connecting rod H¹¹ is moved to the rear to effect a corresponding elongation of the rear link or toggle H⁷, which thus raises the rear ends of the magazines to an extent equal to that of their forward ends; and the lowering of the magazines of course effects the reverse operation of the parts. And the tendency of the magazines to slide forwardly (due to their inclination) is resisted and overcome by the coöperation of the roller H¹³ of the jointed link H⁶ with the track H¹² of the connecting rod H¹¹. As thus constructed, the magazine shifting mechanism will and can only move the magazines upwardly and downwardly in a straight path, thus eliminating any necessity for the use of supplemental guiding devices, etc. To facilitate the raising of the magazines, I have also provided a counterbalancing spring H³ which is of the torsional variety and surrounds the cam shaft H¹, having one end fastened to one of the cams and its other end connected to a projection E¹ of the supporting frame E.

As previously stated, I have shown my invention merely in preferred form and by way of example, and it is obvious that many modifications and alterations therein, and in its mode of application, will suggest themselves to those skilled in the art without departure from its scope. Thus, the cams H¹ may be arranged to coöperate with one of the other parts instead of directly with the magazines; or, if desired, the cams may be replaced by some other shifting device or entirely eliminated and the link or toggle system alone relied upon to effect the raising and lowering of the magazines.

Having thus described my invention, its construction and mode of operation, what I claim and desire to secure by Letters Patent of the United States is as follows:

1. In a typographical machine, the combination of a plurality of magazines, and mechanism for shifting them to bring one or another into operative position, the said mechanism including means incorporated therein to maintain the magazines in a straight or rectilinear path during their movement, thus avoiding the use of supplemental guiding devices.
2. In a typographical machine, the combination of a plurality of magazines, and mechanism for shifting them to bring one or another into operative position, the said mechanism including a system of linkage incorporated therein and operative to maintain the magazines in a straight or rectilinear path during their movement.
3. In a typographical machine, the combination of a plurality of magazines, a shift frame therefor, and mechanism for moving the shift frame to bring one or another of the magazines into operative position, the said mechanism including jointed links or members arranged at opposite ends of the

- magazines and pivoted to the shift frame and a relatively fixed part of the machine respectively, a longitudinal rod connecting the links together, and means coöperating 5 with the connecting rod to insure the movement of the magazines in a straight path as the jointed links are elongated or contracted.
4. In a typographical machine, the combination of a plurality of magazines, a shift 10 frame therefor, and mechanism for moving the shift frame to bring one or another of the magazines into operative position, the said mechanism including jointed links or members arranged at opposite ends of the 15 magazines and pivoted to the shift frame and a relatively fixed part of the machine respectively, a longitudinal rod connecting the links together, and a third jointed link or member facing in a direction opposite to 20 that of the other links and also connected to the shift frame and a relatively fixed part of the machine and having a bearing portion at its joint contacting with said longitudinal connecting rod, for the purpose 25 described.
5. In a typographical machine, the combination of a plurality of magazines, a shift frame therefor, and mechanism for moving the shift frame to bring one or another of 30 the magazines into operative position, the said mechanism including a longitudinal rod having a parallel motion during the movement of the magazines, and means connected to the magazines and coöperating 35 with the rod to sustain the forward thrust of the magazines and maintain them in a straight path during their movement.
6. In a typographical machine, the combination of a plurality of magazines, a shift 40 frame therefor, and mechanism for moving the shift frame to bring one or another of the magazines into operative position, the said mechanism including a longitudinal rod having a parallel motion during the 45 movement of the magazines, and a jointed link or member connected to the magazines and a relatively fixed part of the machine respectively, and having a bearing portion contacting with the under side of the longitudinal rod to sustain the forward thrusts 50 of the magazines and maintain them in a straight path during their movement.
7. In a typographical machine, the combination of a plurality of magazines, a shift 55 frame therefor, and mechanism for moving the shift frame to bring one or another of

the magazines into operative position, the said mechanism including the cam H, the pairs of jointed links H⁵, H⁶ and H⁷, the links H⁵, H⁶ being arranged at the front 60 and connected to the shift frame and a fixed part of the machine respectively, and the links H⁷ being arranged at the rear and connected to the shift frame and a fixed part of the machine, and the longitudinal rod H¹¹ 65 connected to the links H⁵ and H⁷ and coöperating with the links H⁶, substantially in the manner shown and described.

8. In a typographical machine, the combination of a plurality of magazines, a shift 70 frame therefor, and mechanism for moving the shift frame to bring one or another of the magazines into operative position, the said mechanism including a device for imparting movement to the magazines, jointed 75 links or members arranged at opposite ends of the magazines and pivoted to the shift frame and a relatively fixed part of the machine respectively, a longitudinal rod connecting the links whereby they are elongated or contracted to equal extents, and means connected to the magazine shift frame and re-acting against the connecting rod to prevent the movement of the magazines in other than a straight path. 80

9. In a typographical machine, the combination of a plurality of magazines, a shift frame therefor, and mechanism for moving the shift frame to bring one or another of the magazines into operative position, the 85 said mechanism including a device for imparting movement to the magazines, jointed links or members arranged at opposite ends of the magazines and pivoted to the magazine shift frame and a relatively fixed part 90 of the machine respectively, a longitudinal rod connecting the links whereby they are elongated or contracted to equal extents, and a third jointed link facing in a direction opposite that of the others and also pivoted 95 to the shift frame and a relatively fixed part of the machine, and provided at its joint with a bearing portion contacting with the under side of the connecting rod to prevent the movement of the magazines in other 100 than a straight path. 105

In testimony whereof, I have affixed my signature.
